FISH LURE

Thomas R. Hollifield, 4018 Marion Place,
Shreveport, La.

Filed Sept. 15, 1961, Ser. No. 66,723

Term of patent 14 years

(Cl. D31—4)

FIG. 1.

FIG. 2.

FIG. 3.

FIG. 4.

The side not shown is substantially the same as the side shown.

The dominant features of my design reside in the portions shown in full lines.

I claim:

The ornamental design for a fish lure, as shown and described.
